UNITED STATES PATENT OFFICE.

WELLESLEY R. HAMPDEN, OF MILWAUKEE, WISCONSIN, ASSIGNOR OF ONE-HALF TO
HILDEGARDE A. BROECKER, OF MILWAUKEE, WISCONSIN.

AUTO RADIATOR-HEATER AND SIGNAL-LIGHT.

1,242,797.

Specification of Letters Patent.

Patented Oct. 9, 1917.

Application filed February 17, 1916. Serial No. 78,801.

To all whom it may concern:

Be it known that I, WELLESLEY R. HAMPDEN, a citizen of the United States, residing at the city of Milwaukee, county of Milwaukee, and State of Wisconsin, have invented new and useful Improvements in Auto Radiator-Heaters and Signal-Lights, of which the following is a specification.

My invention relates to improvements in devices for both heating the contents of a radiator of an automobile and simultaneously producing a light which at night serves as a signal light for such automobile. While my lighting and heating device is preferably located within the radiator of an automobile the same may, if desired, be located upon the exterior of such radiator, or beneath the hood at one side of the radiator, two forms of construction being illustrated in the accompanying drawings.

My invention is further explained by reference to the accompanying drawings, in which—

Figure 1 represents a perspective view, and Fig. 2 a side view of one end of my device showing the heater located within the radiator inclosure.

Fig. 3 represents a front view, and Fig. 4 a side view of one end of a modified form of my device as it appears when the heater is located outside of the radiator inclosure.

Referring more in detail to the drawing it will be noted that the automobile radiator 2 is provided of substantially the usual construction, having a lower water chamber 3 and upper chamber 4, while an end chamber 11 is in communication with the said chamber 4, but is separated from the lower chamber by a partition 3'. A casing 12 is arranged within the end chamber 11 mounted upon the bottom 14 of the radiator and providing a heater chamber 13 adapted for the reception of a heater or burner 6 having a flame 7 beneath the coils, and arranged upon the bottom of the radiator adjacent an opening 15 therein. The coil 5 is positioned above the burner 6 having one end thereof communicated with chamber 4 through the top 16 of the casing 12, while a lower extension 17 of the coil angularly projects through the inner side of the casing 12 passing downwardly within the chamber 11 and tapped through the partition 3' into the lower chamber 3. Outlet ports 19 are arranged in the front and side of the radiator

for allowing the products of combustion from the burner 6 to pass therethrough, while a regulator 18 is provided for the said burner.

By the device shown in Figs. 1 and 2 the heater 6 and spirally wound heating tube 5 are located within the radiator inclosure 2, while by the form shown in Figs. 3 and 4 the heater 6, spirally wound tube 5 and other coöperating parts are preferably all located outside of the radiator inclosure 2 within an inclosure 8.

9 and 10 are globe valves through which the water enters and escapes from the spiral tube 5.

It will be understood that when the heater is not used the valves 9 and 10 may be closed when the heater 6 may, if desired, be removed.

It will also be understood that, if desired, the chamber 8, together with the coil 5 and heater 6 may be disengaged from the radiator and removed when the temperature does not require their use.

11 is a transparent member which may, if desired, be formed of ordinary glass which is located in front of the flame 7 of the heater, whereby the same flame which is used for heating the contents of the radiator may also be used for a signal light.

While the heater and mechanism connected therewith is shown both in front of and within the radiator I wish it to be understood that the same may, if desired, be located at the rear of the radiator beneath the hood.

I also wish it to be understood that the same liquid which is used for heating the radiator may be connected with the jacket surrounding the cylinder of the engine, whereby the same heater is simultaneously used for heating both the radiator and the liquid in the jacket surrounding the engine cylinders.

Having thus described my invention what I claim as new and desire to secure by Letters Patent is:—

A combined radiator heater and signal light for automobiles comprising in combination with a radiator having communicating top and side chambers and a bottom chamber, a separating partition between the said bottom and side chambers, a casing within said side chamber forming a heater chamber, with the bottom, front and side

walls of the radiator arranged with openings therethrough communicating with the said heater chamber, a burner arranged within the heater chamber upon the bottom 5 of the radiator adjacent an opening provided in the said bottom, a heating coil arranged over said burner having one end tapped through the top of said casing and its other inner end angularly projecting 10 from the inner side of the casing into the side chamber and tapped through the said

partition in communication with the lower chamber and a transparent wall portion provided for the radiator adjacent the said burner.

In testimony whereof I affix my signature in the presence of two witnesses.

WELLESLEY R. HAMPDEN.
